Attorney

UNITED STATES PATENT OFFICE.

EMANUEL J. BOYLER, OF WEST HAVEN, CONNECTICUT, ASSIGNOR TO DUPLEX SNAP FASTENER CO. INC., A CORPORATION OF NEW YORK.

SEPARABLE FASTENER.

1,284,204.

Specification of Letters Patent.

Patented Nov. 5, 1918.

Application filed June 1, 1916. Serial No. 101,062.

To all whom it may concern:

Be it known that I, EMANUEL J. BOYLER, a citizen of the United States, residing at West Haven, in the county of New Haven 5 and State of Connecticut, have invented new and useful Improvements in Separable Fasteners, of which the following is a specification.

This invention relates to improvements in 10 separable fasteners and more particularly to a fastener of the head and socket type.

It is the object of this invention to provide a separable fastener in which the head is engaged by a resilient wire in the socket, 15 from which the head may be readily disengaged.

The advantages of this invention are the simplicity of construction and the small 20 number of parts which cheapen the cost of assembling, and the thinness of the united parts of the fastener when engaged which is extremely desirable as these fasteners are used extensively on ladies' dresses.

While the preferred forms of this invention 25 are illustrated upon the accompanying sheet of drawing yet it is to be understood that minor detail changes may be made without departing from the scope thereof.

Figure 1 is a top plan view of the united 30 fastener.

Fig. 2 is a bottom plan view of Fig. 1.

Fig. 3 is a transverse, central, sectional view through Fig. 1.

Fig. 4 is a view in section taken on the 35 lines 4—4 of Fig. 3.

In carrying out this invention, the fastener includes a head member comprising a disk 1 of light metal having a head 2 struck up centrally thereon, with a restricted neck 40 portion 3, and a socket member comprising a circular base plate 4 of light metal having a central opening 5 of sufficient size for the head 2 to pass therethrough, and circular top plate 6 of light metal secured upon 45 the base plate by spinning a flange 7 from the base plate thereon, with a central aperture 8 adapted to allow of the passage of the top of the head when in place. Both the head and socket members are provided 50 with a plurality of apertures 9 for sewing or otherwise attaching the parts to the dress goods or material carrying the fastener.

Between the top and base plates of the 55 socket member a spring head engaging means is mounted so that when the head is

forced home it will expand the spring which will thereafter contract about the restricted neck of the head and hold the parts together against side strains but release the parts upon a direct pull away from each other. 60

The head securing means comprises a wire spring 10 bent centrally upon itself with the upper portion of the arc of the bend secured between the top and base plates under the base flange, the portions of the 65 spring extend therefrom parallel to each other beyond and on each side of the head receiving aperture 5 with their free ends bent back on the outer sides on a greater arc than the center bend, with the free ends and 70 a contiguous portion of the arcs of their respective bends secured between the top and base plates under the base flange.

The parallel portions of the spring are arranged as to flex and allow the insertion 75 of the head between them and to snap back and engage the restricted neck to hold the head when forced home. Constructing the spring head securing means in this manner not only reduces the cost and time of assembling 80 but also provides greater flexibility of the parallel portions on account of the greater arcs of the bends of the free ends.

In all forms the complete fastener is extremely flat being but little thicker than the 85 height of the head member and this is made possible by the simple construction as above-described. With the exception of the spring all parts are struck from sheet metal and the assembling of the socket is very 90 simple as there are only three parts to be put together and the spring is held between the top and base plates by spinning or crimping the flange from the base plate about the top plate. There are no parts to 95 become disengaged in the socket and the spring, upon which the operation of fastener depends, is completely covered and protected.

What I claim is:—

A separable fastener including a head member comprising a plate; a head thereon; said head being provided with a restricted neck portion; a socket member comprising a base plate provided with an opening 105 through which the head is insertible; said base plate having marginal edges extending at an angle to the plate and bent back to approximate alinement therewith to constitute a retaining flange; an approximately flat top 110

plate provided with a head receiving opening in which a portion of the head is disposed when inserted; and a resilient member having a portion secured between the 5 top plate and base plate beneath the retaining flange, and a portion adapted to releasably engage the restricted neck on the head

member when the head is inserted through the opening in the base plate.

EMANUEL J. BOYLER.
